UNITED STATES PATENT OFFICE

ANDREW RASMUSSEN AND WILLIAM S. GOODELL, OF RACINE, WISCONSIN

AUTOMATIC TRIP DEVICE

Application filed February 20, 1928. Serial No. 255,666.

This invention relates to improvements in automatic trip devices.

It is one of the objects of this invention to provide an automatic trip device, the operation of which is controlled by centrifugal force.

It is a further object of this invention to provide an automatic trip device for use in machines having a rotatable member, the trip device operating automatically when the speed of the rotatable member has diminished, or when said member has entirely ceased to rotate.

It is a further object of this invention to provide an automatic trip device which may be used on barbecue machines having a fire proof curtain, the trip device being adapted to automatically release said curtain when an exigency arises which makes it necessary to insulate the pieces of meat from the fire.

It is a further object of this invention to provide an automatic trip device which is simple in construction and operation, and well adapted for the purpose described.

With the above and other objects in view, the invention consists of the improved automatic trip device, and all its parts and combinations as set forth in the claims, and all equivalents thereof.

In the accompanying drawings, in which the same reference characters designate the same parts in all of the views:

Fig. 1 is a side elevation of the improved automatic trip device, parts being broken away, and parts being shown in section;

Fig. 2 is a sectional view on line 2—2 of Fig. 1;

Fig. 3 is a sectional view on line 3—3 of Fig. 1, showing the position of the parts when the machine is rotating at a high speed;

Fig. 4 is a similar sectional view showing the position of the parts when the machine is rotated at a very slow speed or is not rotated at all.

Referring to the drawings the numeral 8 designates a bearing member, the upper portion of which is provided with a horizontal bore 9, within which is a bushing 10. A shaft 11 is journaled in the bushing, and has

a pulley 12 secured to one end, and a governor member 13 secured to its other end. Secured to the upper part of the bearing member by bolts 14 is one end of an extension 15. The extension 15 is provided with a portion 16 extending at right angles, and having a bifurcated lower end.

The upper end of the portion 16 is provided with a projection 17 having a bore 18 therein. An opening 19 is in connection with the bore. Within the bore is a pin or releasable member 20 having an annular shoulder 21 formed in its lower end. An upward force (not shown) is being exerted upon the pin, and it is normally held against upward movement by the engagement of one end of a bell crank lever 22 with the shoulder 21. The bell crank lever is pivoted at 23 to the member 16, and it is engaged by a spring 24 which normally holds it in locking position.

The bifurcated lower end of the portion 16 has bores 25 therein, within which are insulated bushings 26. Journaled within the bushings is an actuating rod 27 having a pointed end 28. Between the bifurcated ends of the portion 16, is an insulated disk 29 mounted on the rod 27, and held between two nuts which are threaded on the shaft. Adjustment nuts 30 limit the inward movement of the rod. The disk 29 bears against the lower end of the bell crank lever 22, and is adapted to move the latter out of engagement with the shoulder 21 to release the pin upon outward movement of the rod 27.

The governor member 13 has a central bore 31 within which one end of the shaft 11 extends. The governor is held rigidly upon the shaft by means of a set screw 32. The governor is formed with an enlarged hollowed out portion 33 within which an arm 34 is pivoted. The arm 34 has a weight 35 on one side, and on the other side has a beveled extension 36 which is adapted to slide under the pointed end 28 of the rod 27 to cause the rod to move outwardly. The arm is normally held by the spring 38, so as to cover the space 37 in the bore 31 to prevent the end of the rod 27 from entering it. However, upon rotation of the shaft 11, and a consequent rotation of the governor, the

weight 35 on the arm 34 causes the latter to swing outwardly by centrifugal force, thereby exposing the opening and allowing the point of the rod 27 to enter it. When the speed of rotation is decreased, or when rotation stops altogether, the centrifugal force will no longer overcome the tension of the spring 38, and the beveled edge 36 will slide under the point of the rod 27 and force the latter out of the opening. (See Fig. 4.)

The operation of the device is as follows: Assuming that the shaft 11 is revolving at a normal speed, the parts will be in the positions shown by the full lines in Fig. 1 and as shown in Fig. 3. The bell crank lever is engaging the shoulder of the pin 20, and is preventing its upward movement. The arm 35 of the governor is as shown in Fig. 3, thrown out by centrifugal force against the tension of the spring 38, and exposing the opening 37. The point of the rod 27 is in the opening. Now, if through some mishap or other cause, the speed of rotation of the shaft 11 is reduced very much, or if the shaft has stopped rotating, there will either be no centrifugal force acting upon the arm 34, or else it will be so small as not to overcome the force exerted by the spring 38, which will draw the arm inwardly, allowing the bevel 36 to slide under the point 28 of the rod 27, as shown in Fig. 4. This will push the rod outwardly to the position shown by the dotted lines in Fig. 1, causing the disk 29 to move the bell crank lever out of engagement with the shoulder of the pin 20. The pin will then move upwardly in the direction of the force exerted upon it. The pin may be in connection with any safety device desired. In the case of a barbecue machine, the pin is in connection with an asbestos curtain, and automatically releases it when the speed of the mechanism turning the meat is so slow that there is danger of the meat burning. When such is the case, the automatically lowered curtain insulates the meat from the fire to prevent its being scorched.

An electric bell or other signal 39 is used in connection with the device. One wire from the signal is attached to the rod 27. The other end is secured to a portion of the frame of the device such as the bolt 14. Whenever the speed of rotation of the shaft 11 is so decreased as to cause the arm 35 to engage the end of the pin 27, the contact to the signal will be completed, and a warning will be given at the same time that the automatic release takes place.

It is not desired to limit the scope of this invention to any particular adaptation, as the broad concept contemplates the use of the device on machines generally.

From the foregoing description it may be seen that the improved automatic trip device is simple in construction and operation, and well adapted for the purpose described.

What we claim is:

1. The combination with a releasable member, of a trip device therefor, comprising a frame, means on said frame normally engaging said releasable member, actuating mechanism engaging said means, a rotatable member in connection with said frame, a governor on said rotatable member having an opening therein, and a centrifugally operated arm on the governor regulating the admission of a portion of the actuating mechanism to the opening in the governor. 70

2. A trip device comprising a frame, a releasable member, means of said frame for engaging said releasable member, actuating mechanism engaging said means, a rotatable member in connection with the frame, a governor having an opening therein on said rotatable member, a centrifugally operated arm pivoted on the governor and having a beveled portion for engaging a portion of the actuating mechanism, and yielding means for exerting a force on the arm in a direction opposite to the centrifugal force. 80

3. A trip device comprising a frame, a releasable member, a bell crank lever for engaging said releasable member, yielding means for holding said bell crank lever in engaging position, an actuating rod having a pointed inner end slidably positioned in the frame, a disk on the rod engaging the bell crank lever, a rotatable member in connection with the frame, a governor having an opening therein on the rotatable member, a centrifugally operated arm pivoted on the governor and having a beveled portion for engaging the pointed inner end of the actuating rod, and yielding means for exerting a force on the arm in a direction opposite to the centrifugal force. 90

In testimony whereof we affix our signatures.

ANDREW RASMUSSEN.
